I. B. MILLNER.
HAND OPERATED AIR DASH WASHER.
APPLICATION FILED SEPT. 1, 1920.

Patented May 17, 1921.

7 Inventor
J. B. Mullner

UNITED STATES PATENT OFFICE.

ISAAC B. MILLNER, OF WASHINGTON, DISTRICT OF COLUMBIA.

HAND-OPERATED AIR-DASH WASHER.

1,378,600.

Specification of Letters Patent. Patented May 17, 1921.

Application filed September 1, 1920. Serial No. 407,478.

To all whom it may concern:

Be it known that I, ISAAC B. MILLNER, a citizen of the United States, residing at Washington, District of Columbia, have invented certain new and useful Improvements in Hand-Operated Air-Dash Washers, of which the following is a description, reference being had to the accompanying drawing and to the figures of reference marked 10 thereon.

This invention relates to devices for washing fabrics, and more particularly to a hand-held device for washing smaller fabrics, such as handkerchiefs and undergarments of 15 finer quality.

An object of this invention is to provide a hand-held device which can be readily used for quickly and efficiently washing fine linen or small pieces of wearing apparel in a 20 basin or stationary washstand or small receptacle.

A further object of this invention is to provide a hand-held device including a striking element adapted to be projected 25 against the fabric to loosen the dirt, the device being constructed and arranged to simultaneously cause the air to pass through the mesh of the fabric to carry away the loosened dirt.

30 Still another object of this invention is to provide a device of the above character including a relatively movable cylinder and piston adapted to be held in the hand, and including a fabric contacting member, said 35 parts being constructed and arranged so that when the device is projected against the fabric, the contact member will loosen the dirt from the fabric while a blast of air is jetted through the meshes of the fabric to 40 carry the dirt away.

Yet another aim of this invention resides in forming the fabric contact member as a collapsible cup-shaped element formed with 45 separate relatively movable scrubbing fingers on the rim thereof and provided with adjacent air outlets, the fabric contacting member having an air inlet connection about the hand held cylinder so that when the cylinder and fabric contacting member are projected against the fabric, the blast of air 50 will pass upon the scrubbing fingers through the mesh of the fabric as the fingers are given a scrubbing action against the fabric by the operation of the device.

55 These and other objects will in part be ob-

vious and will in part be hereinafter more fully disclosed.

Referring more particularly to the accompanying drawing—

The figure illustrates a cross section of one 60 form of the invention.

In general, the invention comprises a collapsible cup-shaped member connected by means of a rigid tube to a piston reciprocating within the cylinder, which is adapted to 65 be held in the hand of the user. This cylinder constitutes an air chamber which has suitable valved ports leading to the atmosphere and to the hollow tube connected to the cup-shaped member, the device being so 70 constructed that when the device is held in the hand and projected against a fabric partly submerged in soapy water, the cup-shaped member will strike the fabric to loosen the dirt therefrom, and an air blast 75 will be forced from the air cylinder by way of the hollow tube, through the mouth of the cup-shaped member and thence through the mesh of the fabric to carry away the dirt loosened by the suds and by the force of impact of the cup-shaped member.

Referring more particularly to the accompanying drawing, the preferred form of the device comprises a hollow cup-shaped member 1 preferably made of rubber or other 85 resilient material provided on its open edge with a series of scrubbing fingers or corrugations 2 formed for the purpose of more easily loosening the dirt, and provided at its top with an open flange 3 forming a means 90 for its attachment to a rigid tube 4 of any desired material. As shown clearly in the drawing, this flange 3 forms an opening 5 adapted to be controlled by a one-way valve 6 suitably attached to the shoulder 7 of the 95 cup-shaped member 1.

It is of course obvious that any arrangement of a one-way valve may be substituted. The upper end of the rigid hollow tube 4 has formed integral therewith a piston 5 working within the air cylinder 6. This piston may be fixed to the upper end of the tube in any suitable manner such as by holding it between a small flange 8 on the end of the tube and the crimped portion 9. 100 The air cylinder 6 is suitably closed at its lower end by means of a cap 10 provided with a central bore 11 through which slidably passes the tube 4, there being suitable packing 12 arranged at this point to provide 105 110

a guide for the reciprocation of the piston in the cylinder. The opposite end of the cylinder 6 is provided with a valved air inlet port which may be suitably located and 5 of any desired form. In the present construction, the end of the cylinder 13 is formed with a central bore 14 threaded to receive a valve cage 15, having a spherical ornamental dome 16, and a base portion 17 10 provided with a series of air inlets 18. Any manner of one-way valve may be used, but in the present instance it is desired to affix to the bottom of the cage 17 the ordinary type of one-way valve 19. Located between 15 the top of the cylinder and the piston is a coiled spring 20 adapted to normally force the piston to that end of the cylinder opposite the inlet port 18.

In operating this device, the fine wearing 20 apparel, linen or other fabric, is immersed in soapy water and the device is then held in the hand so that the cup-shaped member will be projected more or less violently against the article to be cleansed, the force 25 of the blow depending upon the fabric and the adherence of the dirt in the mesh of the fabric. As the cup-shaped member 1 strikes the article the scrubbing fingers 2 will be given relative movement against the face of 30 the fabric at the same time, relative movement between the cylinder 6 and piston 5 will be created, and the air contained in the upper end of the air cylinder will be forced through the hollow tube 4 out through the 35 flat valve 6 and through the scrubbing fingers and thence through the fabric mesh, carrying away the dirt loosened by the suds and the impact of the blow. The spring 20 need be just strong enough to lift the air 40 cylinder 6 and restore the parts to the position shown in the drawing. During this reverse movement between the piston and the cylinder, air will be drawn in through the ports 18, past the flat valve 19 and into the 45 air cylinder 6, the flat valve 6 in the cup-shaped member 1 closing at this time, so that water will not be drawn into the interior of the air cylinder.

It is obvious that by means of this 50 convenient little device, ladies may very quickly and efficiently wash fine linen and undergarments in stationary wash-stands. Due to the impact of the article contacting member, and the jet of air passed through the 55 mesh of the fabric, the dirt is most effectively loosened and carried away. So also, by providing a collapsible or a rigid cup-shaped member, the rubbing and pounding effect of this member is greatly augmented. 60 It is of course within the spirit of this invention to use a rigid member, if desired.

It is obvious that minor changes in the details of construction and the arrangement of parts may be made without departing from the spirit of the invention as set forth 65 in the appended claims.

Having thus described the invention, what I claim as new and desire to secure by Letters-Patent, is—

1. A device for washing fabrics comprising a member adapted to be projected against the fabric to be washed to loosen the dirt, said member having a plurality of fabric engaging fingers formed with adjacent air outlets, and means operated by the projection of said member against a fabric for causing a flow of air into said member and outwardly through said outlets whereby to force air about said fingers and through the mesh of said fabric to assist in removing the 80 dirt.

2. A hand-held device for washing fabrics comprising a member adapted to be projected by the hand against the fabric to be washed, said member having relatively movable scrubbing portions and air outlets arranged adjacent thereto, and means operated by the projection of said member against a fabric for causing a flow of air into said member and outwardly through 90 said outlets whereby to pass through the mesh of said fabric.

3. A hand-held device for washing fabrics comprising a collapsible cup-shaped member having relatively movable scrubbing fingers 95 and adjacently located air outlets on the rim thereof, an air cylinder having an air inlet port, a piston reciprocable in said cylinder and rigidly connected to said cup-shaped member, and means for permitting a flow of 100 air through said air cylinder into said cup-shaped member and radially through said perforations when said device is projected against the fabric to be cleansed.

4. A device of the character described 105 comprising a cylinder adapted to be held in the hand and provided with a suitable valve controlled air inlet port, a piston reciprocable in said cylinder, a rigid hollow tube connected to said piston and passing through 110 one end of said cylinder, an open-ended collapsible cup-shaped member rigidly connected to the opposite end of said rigid tube and provided with air outlets through the fabric contacting portion thereof, a valve controlled 115 air conduit connecting said hollow chamber and cup-shaped member, and a spring arranged in said air cylinder between said piston and one end thereof.

In testimony whereof, I affix my signature. 120

ISAAC B. MILLNER.
